UNITED STATES PATENT OFFICE.

HERMANN LEMP, OF LYNN, MASSACHUSETTS, ASSIGNOR, BY MESNE ASSIGNMENTS, TO GENERAL ELECTRIC COMPANY, A CORPORATION OF NEW YORK.

FLASH-BOILER.

No. 841,792.

Specification of Letters Patent.

Patented Jan. 22, 1907.

Application filed October 2, 1902. Serial No. 125,670.

To all whom it may concern:

Be it known that I, HERMANN LEMP, a citizen of the United States, residing at Lynn, county of Essex, State of Massachusetts, have invented certain new and useful Improvements in the Operation of Flash-Boilers, of which the following is a specification.

It is well understood that the flash-boiler as commercially built has only a limited storage-space for water and steam, and it is because of this limitation that such boilers are free from dangerous explosions. In its simplest form a flash-boiler comprises a coil of tubing, which is subjected to the fire-gases and into which fluid, usually water, is pumped. In circuit with the boiler is commonly placed a safety or relief valve, which opens when the pressure reaches a certain predetermined point and discharges steam or water, or a combination of both, back into the water-tank. This action generally occurs when the vehicle is standing still or when the engine is consuming a comparatively small amount of energy and the fire is hot. When such an action takes place, a large portion of the water and steam is discharged from the boiler. Hence it becomes necessary to supply an additional amount of water before the vehicle can be started. Owing to the fact that the power of the generator to furnish steam at this time is practically *nil*, it becomes necessary to provide an auxiliary pump in addition to the power-pump, which is capable of independent operation. This auxiliary pump is usually operated manually, and its use is objectionable for obvious reasons.

It sometimes happens under extremely heavy loads that the power-pump employed to supply water to the boiler is insufficient. This is due principally to the fact that the speed of the engine is low, and consequently that of the pump. In cases of this kind the water-supply has to be augmented by the auxiliary pump.

The present invention has for its object to overcome the objections above pointed out and to provide a means whereby the effective capacity of a flash-boiler can be increased without increasing the storage-space that is subjected to the fire-gases, thereby enabling the system to be more readily started and at the same time increasing its flexibility.

In carrying out my invention an accumu-

lator-tank is provided which is placed in circuit with the water-supply pipe between the boiler and the source of water-supply. This accumulator is so arranged that it is free at all times to receive water from the boiler, but is prevented from returning it thereto except under certain conditions—*i. e.*, when the operator desires more water admitted to the boiler and opens a valve for that purpose. The cubical contents of the tank should be considerably greater than those of the boiler. I have found a ratio of three to one to be satisfactory; but this can be varied without departing from my invention. Where water under considerable pressure can be obtained, it may be supplied directly to the boiler and the accumulator; but for automobile service it is necessary to use a pump. This pump may be of any suitable construction and should be arranged to deliver water to the boiler as it is needed. The effective delivery of the pump can be regulated by any suitable means. I have found that an elastic pump arranged to deliver water at an average of two hundred and fifty pounds per square inch, with a maximum of five hundred, operates satisfactorily. The elastic medium between the driving element and the pump should be so arranged that the amount of water delivered by the pump can be varied from a minimum to a maximum, depending on conditions. In circuit with the accumulator is a pump which is designed to deliver air thereto up to a predetermined maximum. The air-pump may be actuated manually or by power. In the latter case it may operate continuously or only at intervals, as desired. In the present embodiment of my invention the pump is continuously driven by the same means which drive the water and fuel pumps, and its effective delivery is correspondingly varied with that of the water-pump. I have found that an initial pressure of two hundred pounds per square inch is sufficient for relatively light vehicles; but the pressure can be varied to meet any given condition. An amount of water sufficient to maintain a seal is kept in the accumulator at all times. The pump should be so constructed that it is capable of maintaining or raising the initial air-pressure in the accumulator to the desired point. Between the accumulator and the boiler is a check-valve which permits water

to enter the accumulator either from the boiler or pump, or from both, under excess pressure on the boiler, but prevents it from returning except under the control of the operator. Surrounding the check-valve is a by-pass which is provided with a manually-actuated valve that is preferably so located that it may be controlled from the vehicle-seat. When for any reason the supply of water of the boiler is inadequate, as in starting or climbing a hill or when working under an abnormal load, the operator can by opening the by-pass admit enough to start the system into operation. Owing to the fact that the accumulator is relatively large and is always under initial air-pressure, it follows that a certain amount of water is available at all times, and when for any reason the boiler has been emptied, such as by overheating when the engine is not consuming steam and the fire is hot, a large amount of more or less heated water is instantly available and at a relatively high pressure. To put the matter in a different way, the accumulator always contains a certain amount of water, so does the boiler, and when the boiler discharges back into the accumulator, due to increased pressure, instead of delivering the water to the supply-tank, where it rapidly cools, it delivers it to a tank that is already working under a relatively high pressure, where the temperature is preserved. As the amount of water in the boiler decreases in this manner the amount in the accumulator-tank correspondingly increases until finally equal pressures are attained in both. Manifestly when the throttle-valve is opened to admit steam to the engine the boiler-pressure falls below that of the accumulator and the latter feeds to the former.

In the accompanying drawing, which illustrates an embodiment of my invention, I have shown diagrammatically a flash-boiler and burner with the necessary adjuncts for supplying them with water and fuel.

In the drawing is represented a flash-boiler of any suitable construction, which is arranged to supply superheated steam to the engine 2, a suitable throttle-valve 3 being employed to control the speed of the engine. Surrounding the boiler is a casing 4, and situated in the bottom thereof is a hydrocarbon-burner 5. The upper end of the boiler-casing is provided with an upwardly-opening flue 6 and with a downwardly-opening flue 7. The exhaust from the engine passes into the chamber 8, formed in the upper part of the boiler-casing, where it is reheated and rendered invisible at ordinary atmospheric conditions. The exhaust passes from the chamber into the downflue and creates a forced draft. Water for the system is supplied from the water-tank 9 or other source of supply. The tank may have a pressure corresponding to that of the atmosphere or it may

differ therefrom. In circuit between the boiler and the water-supply is a power-driven pump 10. This pump has to work against the boiler-pressure, and hence is necessary in a system depending upon an ordinary tank for its supply. The pump illustrated is capable of varying its effective delivery by varying its stroke to suit the conditions of operation. In the present instance the pump is driven from the shaft 11 by means of an eccentric, which eccentric is connected to the piston of the pump through an elastic or yielding medium 12. When the pressure on the boiler is less than a certain point, the pump-piston will work full stroke; but as the pressure increases the stroke shortens and the balance of the movement of the eccentric is absorbed by the elastic medium and given out on the return stroke. As shown, the shaft 11 is connected to the engine by chain gearing 13, as indicated in dotted lines; but, if desired, the pump or pumps may be driven by a separate source of power. The pistons of the pumps are withdrawn from the cylinder by the extension-springs 14. When the pressure on the delivery side of the pump exceeds a certain predetermined amount, the pistons stand still and the stroke of the eccentric is taken up in the elastic connection 12. The power water-pump is provided with the usual suction-valve 15 and the delivery-valve 16.

In order to start the system into operation when there is no available energy for driving the power-pump and the water in the accumulator is low, I provide a manually-actuated water-pump 17, which is provided with a suction-valve 18 and a delivery-valve 19. The pump is operated by a hand or foot lever 20, which is pivotally supported in a suitable manner. It is to be observed that the check-valves in the two pumps are correspondingly placed, so that when the power-pump is idle the water from the manually-actuated pump is free to pass to the boiler.

Situated at a convenient point between the pumps and the boiler is an accumulator or tank 21. The cubical contents of this tank should be considerably larger than the cubical contents of the flash-boiler. No attempt has been made in the present drawing to show the relative proportions between the parts; but I have found by actual practice that if the cubical contents of the tank 21 are about three times as great as those of the boiler satisfactory results can be obtained. The accumulator is connected to the water-delivery pipe of the boiler by a pipe 22. In a circuit with the pipe is a check-valve 23, which opens toward the tank and tends at all times to hold the pressure therein. Surrounding the check-valve 23 is a by-pass 24, containing a manually-actuated valve 25. The latter is preferably located within easy reach of the operator. The valve is so con-

structed and arranged that when it is closed the pressure in the tank is maintained; but when it is open the pressure is permitted to drop and supply water to the boiler, as will 5 hereinafter appear.

Connected to the pipe 22, which leads to the accumulator, is a pipe 26, that leads to the air-pump 27. In circuit with this pipe is a check-valve 28, which opens toward the 10 tank. The air-pump may be of any suitable construction so long as a definite pressure can be maintained on the tank to keep the same potentially energized and ready for immediate service. The one shown is provided 15 with a screen 29 at the point of suction and is so proportioned that it will automatically maintain an air-pressure on the tank of two hundred pounds to the square inch. I have found this pressure to be satisfactory in certain 20 kinds of work; but it can be altered to meet any given condition without departing from my invention. The pump in the present illustration is driven by the shaft 11, which drives the water-pump; but it can be 25 separately actuated, if desired, either by power or manually. Sufficient water is kept in the accumulator at all times, as is indicated at 30, to form a water seal. Situated in the air-delivering pipe 26 is an inlet-valve 31, corresponding to the valve in an ordinary 30 vehicle-tire. The object of this valve is to permit of the application of a manually-actuated pump or source of air under pressure for the purpose of placing the accumulator 35 under an initial pressure when the pump 27 is not working.

In circuit between the accumulator and the boiler is a relief-valve 32, which is preferably connected to the water-tank by a suitable pipe; but it can be located in the tank itself, if preferred. The valve may be set for any predetermined maximum. I have found six hundred pounds to be satisfactory. Under ordinary conditions of operation this 45 relief-valve would not be operative; but it is used to avoid injury to the boiler in case the accumulator fails to operate. In other words, it is a safety device. For example, the accumulator-tank might spring a leak and permit 50 all of the air to escape, in which case it would no longer act as an elastic cushion, for it would fill with water.

The fuel for the burner is supplied from the tank 33, which is placed under an initial air-pressure by the pump 34. In order to increase the pressure of the fuel-supply between the tank and the burner, a fuel-pump 35 is provided having the usual section and delivery valve. In the present illustration the 60 pump is driven from the shaft 11; but it can be driven by separate means, if desired. With the apparatus arranged as shown the water and fuel pumps are adjusted to deliver water and fuel in proportionate amounts, and 65 by reason of the flexible medium 12 the sup-

plies of water and fuel will be correspondingly varied. As the water-pressure on the boiler increases the stroke of the water-pump will be correspondingly decreased and also that of the fuel-pump. In this manner accurate compensation for the changes in load are obtained. It follows from this that the supplies of water to the boiler and fuel to the burner are correlated and bear a definite interdependent relation to each other. 70

The action of my invention is as follows: Assuming that the parts are in running condition and for some reason the demand on the boiler ceases, the pressure on the boiler will rapidly increase, owing to the fact that 80 the boiler parts are hot and also to the fact that it is necessary to keep a small flame in continuous operation. If this condition of affairs continues for some time, the pressure in the boiler will increase to such an extent 85 that it will force water or steam, or both, back into the accumulator 21 or cause the water to enter direct from the pump or from both the pump and boiler, where it will be retained by the check-valve 23. As the water 90 and steam pass from the boiler into the accumulator it is obvious that the air contained therein is compressed to a greater or less degree. Consequently the pressure on the tank is increased above that due to the air-pump 27, and the check-valve 28 holds said 95 pressure and maintains the tank potentially energized to a corresponding degree. Assume now that the boiler is called on to deliver steam. The throttle-valve is opened, and 100 in order to start the engine it is necessary to force more water into the boiler, and if the vehicle is standing still or the engine is not running, in case the invention is applied to a stationary outfit, it is necessary to depend on 105 some means other than the power-pump. It is possible to utilize the manually-actuated pump 17 for this purpose; but, as before stated, its use is highly objectionable, due largely to the fact that it is inconvenient and 110 also because it requires considerable energy. I avoid the use of this pump by means of the accumulator, and to accomplish this the valve 25 is open, which permits hot water or steam, or both, to flow from the tank around 115 the check-valve 23 into the boiler, from which it is delivered as steam to the engine. As soon as the pump starts into operation and its pressure overcomes that of the accumulator it will deliver water to the boiler and the ac- 120 cumulator will remain idle. It will, however, have at least two hundred pounds pressure thereon or whatever pressure the air-pump 27 is adjusted for. After the system is well under way the valve 25 can be closed, 125 and the normal operation of the parts will continue. Assuming that the vehicle is coasting and that the engine is taking little or no steam, the same condition of affairs will take place. 130

As the check-valve 23 opens inwardly toward the accumulator water is capable of passing into the accumulator directly from the pump, as when the boiler is taking little or no water, or it can pass from the boiler and pump at the same time until the pressure is such that the stroke of the pump-actuator is absorbed in the elastic driving device.

I have found the accumulator to be of great assistance in hill-climbing, where there is an extra demand for water. With the system formerly in use it was customary to assist the power-pump by a manually-actuated pump; but this was objectionable for obvious reasons. With the system described the pressure on the accumulator can be depended upon at all times to assist the water-pumps by opening the valve 25, since there is at all times a substantial pressure on the tank. Another advantage in utilizing the accumulator resides in the fact that if the boiler-pressure increases above a certain predetermined point and forces hot water and steam into the accumulator it will be returned to the boiler as soon as the valve 25 is open, and hence the heat units contained therein are rendered available, whereas with the former system of operation, having a relief-valve which was connected to the water-tank, the heat contained in the water discharged from the boiler into the tank was practically wasted.

Assuming that the vehicle is coasting, the following action takes place: The pressure on the accumulator is initially two hundred pounds per square inch, and the water-pump 10 gives an average pressure of two hundred and fifty pounds per square inch, with a maximum of five hundred pounds. This means that as the pump-pressure increases the supply of water will divide between the boiler and the accumulator in accordance with the pressure existing therein. When the boiler-pressure increases to five hundred, then all of the water from the pump will be delivered to the accumulator until its pressure is five hundred, and when this point is reached the pump will stop working, because its maximum has been reached, and the stroke of the eccentric will be taken up by the elastic connection 12. If now the boiler-pressure is lowered, as by drawing steam, the demand for water may be satisfied by the pump or the accumulator or by a combination of both.

A sudden demand on the engine for power would naturally tend to reduce the speed of the vehicle, and in so doing the effective delivery of the pump would be affected, and at this point the accumulator comes into play.

In shutting down after a period of running care should be exercised that the valve 25 is closed, so as to retain the available pressure for starting. This also serves to prevent

water from leaking into the engine in case of 65 poor-fitting valves.

From the foregoing it will be seen that the accumulator stands ready at all times to supply water to the boiler either for starting purposes or to augment the action of the power-pump.

I have described a system taking water from a tank at atmospheric pressure, since it has great utility in connection therewith; but it is to be understood that certain advantages will follow from the use of my invention if a greater pressure is employed.

I have described my invention in connection with a water system; but it can obviously be applied to a fuel system without 8c departing therefrom.

In accordance with the patent statutes I have described the best embodiment of my invention now known to me; but it is to be understood that the apparatus shown is 85 merely illustrative and that the invention can be carried out by other means.

What I claim as new, and desire to secure by Letters Patent of the United States, is—

1. In combination, a receptacle adapted 90 to receive a fluid, an accumulator therefor potentially energized by the pressure of the fluid in the receptacle and means for maintaining the accumulator in the energized state.

2. In combination, a receptacle adapted to receive a fluid under pressure, a source of fluid-supply therefor, and a controllable accumulator for delivering fluid to the receptacle under certain conditions, the same being potentially energized by the combined action of the fluid-pressure in the receptacle and the fluid-supply thereto.

3. In combination, a boiler, a pneumatic means controlling a supply of fluid thereto, 105 means dependent upon the fluid-pressure in the boiler for potentially energizing the pneumatic means, and means controlling the supply of fluid to the boiler.

4. In combination, a boiler, a source of 110 water-supply, an accumulator that is connected to the boiler, an automatic means for maintaining the accumulator under pressure, and a controllable means for subjecting the boiler to the accumulator-pressure when the 115 pressure on the latter exceeds that of the former.

5. In combination, a fluid-receptacle, an accumulator connected therewith, a means between the receptacle and accumulator 120 which admits fluid to the latter and retains it therein, and a controllable means which is adapted to coöperate with the first means for retaining fluid delivered to the accumulator and operates independently of said means for permitting fluid to be discharged from the accumulator to the receptacle under 125 certain conditions.

6. In combination, a fluid-receptacle, an accumulator which is connected to the receptacle, a valve which permits fluid to enter the accumulator when the pressure on the receptacle rises above a certain point and to retain the fluid therein, and a controllable valve which co-operates with the first valve to retain the fluid in the accumulator or permits the fluid to return to the receptacle when the pressure of the latter is below that of the accumulator. 70
7. In combination, a source of liquid-supply, a flash-boiler, an accumulator which is connected to the boiler, a valve which permits fluid to enter the accumulator from the boiler but prevents it from returning, and a second valve which normally prevents fluid from passing in either direction and is adapted to control the passage of fluid from the accumulator to the boiler. 75
8. In combination, a flash-boiler, an accumulator, a connection from the boiler to the accumulator, a pump arranged to deliver water to the boiler and the accumulator, a pump for maintaining the accumulator under an initial air-pressure, a valve which permits water to be discharged from the boiler into the accumulator, and a manually-actuated valve for admitting water to the boiler from the accumulator when the pressure on the latter exceeds the former. 80
9. In combination, a flash-boiler, an accumulator which is connected to the boiler and is under pressure, an engine, a controlling-valve therefor, and a manually-actuated valve for regulating the discharge of water from the accumulator to the boiler when the engine-controlling valve has reduced the boiler-pressure to a point below that of the accumulator. 85
10. In combination, a flash-boiler, an elastic cushioning device connected therewith which stores up energy from the boiler under certain conditions and gives it back at others, and a controllable means for regulating the return of energy from said device to the boiler, substantially as described. 90
11. In combination, a flash-boiler, a source of fluid-supply, and an accumulator for the boiler adapted to receive fluid from the source of supply or the boiler and having controlled communication with the boiler for supplying fluid thereto whereby the boiler may be supplied independently from the source or from the accumulator. 95
12. In combination, a flash-boiler, separate sources of fluid-supply thereto, one being constantly under pneumatic pressure and the pressure thereof being varied by the pressure of the fluid in the boiler, and manually-controlled means whereby the fluid-supply under pressure may be delivered to the boiler. 100
13. In combination, a flash-boiler, separate sources of fluid-supply therefor, one being constantly under air-pressure and adapt- 105
- ed to be supplied either singly or conjointly from the other source and the boiler, and means for controlling the delivery of fluid from the source thereof under pressure to the boiler. 110
14. In combination, a flash-boiler, separate sources of liquid-supply therefor, one of the sources being under air-pressure and rendered potentially operative by the fluid-pressure in the boiler, and means whereby the liquid under air-pressure may be supplied to the boiler either independently of or conjointly with the other source of supply. 115
15. In combination, a flash-boiler, an accumulator therefor, an air-supplying means tending to maintain a constant initial pressure of air therein, and a plurality of means which may act independently or conjointly to vary the pressure in the accumulator. 120
16. In combination, a flash-boiler, a source of liquid-supply therefor, a separate controllable source of liquid-supply connected with the boiler, and automatically-actuated means whereby the latter source becomes a relief and storage-reservoir for heated liquid and vapor from the boiler under certain conditions. 125
17. In combination, a flash-boiler, an automatic relief device for receiving fluid from the boiler, and a normally closed means adapted to be manually operated whereby the relieved fluid may return to the boiler when the pressure of the latter becomes lower than that of the relief device. 130
18. In combination, a flash-boiler, a pump for supplying liquid to the boiler under a high pressure, an automatic relief device for receiving fluid from the boiler through a wide range of pressure, and manually-controlled means for storing the relieved fluid and for returning the same to the boiler independent of the pump. 135
19. In combination, a flash-boiler, a source of liquid-supply therefor, an automatic relief device for receiving and storing up fluid under pressure from the boiler, and controllable means for returning the relieved fluid simultaneously with the liquid being supplied to the boiler to meet abnormal demand or for returning the same independently. 140
20. In combination, a boiler, an accumulator therefor consisting of a body of air which constitutes the potentially-active agent and a body of water which constitutes the accumulative medium, means for augmenting the energy of the potentially-active agent by the pressure of the boiler, means whereby the accumulative medium is automatically maintained under the augmented pressure of the potentially-active agent, and manually-actuated means for controlling the supply of the accumulative medium to the boiler. 145
21. In combination, a boiler, and an accumulator operatively connected therewith and adapted to receive fluid from the boiler. 150

under certain conditions and automatically to retain the same therein independently of change in the conditions of the boiler.

22. In combination, a boiler, an accumulator, a source of water-supply, means for delivering water separately to the boiler or accumulator or to both, and a means automatically varying the quantity of water delivered by said means according to the variations in the pressure of the boiler.

23. In combination, a boiler, a source of water-supply, a variable-stroke pump capable under certain conditions of supplying water directly to the boiler and varying its output according to the pressure in the boiler, and an accumulator for the boiler and operatively connected with the pump whereby the range of effective operation of the latter is augmented.

24. In combination, a boiler, a water-supply system therefor, a pump having an automatically-varying stroke according to the pressure in the system, and accumulator for the boiler whose pressure rises correspondingly with that of the boiler and falls independently thereof.

25. In a steam - generating system, the combination of a boiler, a burner, a source of water-supply, a source of fuel-supply, automatic means for delivering fuel and water respectively to the burner and boiler in definite proportionate quantities, a means controlled by the boiler-pressure whereby the deliveries may vary in definite relation to each other, and controllable means independent of the automatic means for varying the quantity of water delivered to the boiler.

26. In a steam - generating system, the combination of a boiler, a burner, a source of water-supply, a source of fuel-supply, an automatic means for delivering fuel and water respectively to the burner and boiler in definite proportionate quantities, means controlled by the boiler-pressure whereby the deliveries may vary in definite relation to each other, and controllable means for supplying water to the boiler independently of that delivered by the automatic means or simultaneously therewith under abnormal demands for water.

27. In a steam - generating system, the combination of a generator, an accumulator therefor, a burner, a source of water-supply, a source of fuel-supply, means for supplying water to the generator and accumulator, means for supplying fuel to the burner, and a means controlled by the variations in the pressure of the generator for varying the quantitative relation between the supplies of water and fuel.

28. In a steam - generating system, the combination of a generator, an accumulator therefor, a burner, a source of water-supply, a source of fuel-supply, means for supplying

water to the generator and accumulator, means for supplying fuel to the burner, means controlled by the pressure in the generator for regulating proportionately the supplies of water and fuel, and manually-operated means for controlling the accumulator whereby the quantity of water supplied to the boiler may be varied respecting its proportionate relation to the fuel-supply.

29. In combination, a boiler, a main source of water-supply at atmospheric pressure, an auxiliary source of water-supply maintained under air-pressure, automatic means which tend to supply water from the main source to the boiler and to the auxiliary source at substantially constant pressure, and means for maintaining a supply of air on the auxiliary source.

30. In combination, a water-supply system, an accumulator therein, and a generator adapted to receive water independently from either, said accumulator being in controlled communication with the generator respecting the delivery of water to the latter and in open communication with the generator for receiving water therefrom.

31. In combination, a water-supply system, an accumulator therein, a generator, a single conduit connecting the generator with said system and accumulator, means whereby the accumulator may store up and retain fluid received from the generator during abnormally high pressure thereof, and manually-controlled means for returning the fluid to the generator.

32. In the water-supply system for steam-generators, the combination of the generator, an accumulator, a single conduit connecting the two and automatically controlled for permitting the passage of water solely from the former to the latter, and a manually-controlled means coöperating with said conduit whereby the accumulator may supply the generator.

33. In a water-supply system, the combination of a generator, a water-supply pipe therefor, an accumulator connected with the water-supply pipe, an automatic inlet-valve whereby the accumulator may receive water from the generator or supply pipe, and a controlled by-pass shunting the valve whereby the accumulator may supply the generator.

34. In a water-supply system, the combination of an accumulator adapted to receive water from separate sources through a single inlet, a valve for preventing the delivery of water from the accumulator, a by-pass shunting the valve, and a manually-actuated means controlling the by-pass.

35. In a combination, an accumulator, a T-pipe connection, a valve therein controlling the passage of liquid through the same solely in the direction to the accumulator, connection with a source of air-supply be-

tween the valve and the accumulator, a by-pass extending around the valve, and a manually-actuated valve in the by-pass.

36. As an article of manufacture, an accumulator comprising a hermetically-sealed tank, a single pipe connection therefor, an automatic inwardly-opening check-valve in the connection, a by-pass extending around the check-valve, and a hand-valve in the by-pass.

37. As an article of manufacture, an accumulator comprising a tank, a single pipe con-

nection therefor, an inwardly-opening check-valve in the connection, a by-pass extending around the check-valve, a hand-valve in the by-pass, and a connection for a supply of air intermediate the check-valve and tank. 15

In witness whereof I have hereunto set my hand this 30th day of September, 1902.

HERMANN LEMP.
